BEARING-SHIM VISE.

1,315,372.

Specification of Letters Patent.

Patented Sept. 9, 1919.

Application filed September 26, 1917, Serial No. 193,314. Renewed July 8, 1919. Serial No. 309,480.

To all whom it may concern:

Be it known that I, ANDREW B. LOCKHART, a citizen of the United States, residing at Redlands, in the county of San Bernardino 5 and State of California, have invented a new and useful Bearing-Shim Vise, of which the following is a specification.

The invention relates to a shim holder, and more particularly to the class of vises for 10 clamping bearing shims used in automobiles.

The primary object of the invention is the provision of a vise or holder of this character, which may be conveniently 15 clamped to a plank in the work pit of an automobile repair shop for the holding of bearing shims to permit the filing thereof, thereby avoiding unnecessary steps of the workman to a work bench, and which may 20 be placed in an ordinary bench vise at the option of the user, thereby making the tool handy and convenient for quick use.

Another object of the invention is the provision of a vise or holder of this character, 25 wherein the formation of raised burs or the displacement of metal from the edges of the bearing shim is eliminated, when it is being worked upon.

Further objects of the invention are the 30 provision of a vise or holder of this character, which is simple in construction, readily and easily adjusted both for accommodating the different sizes of shims, and for the fastening of the device upon a plank, or 35 in a bench vise, which is capable of firmly clamping a bearing shim, and which is strong, durable, and inexpensive to manufacture.

With these and other objects in view, the 40 invention consists in the features of construction, combination, and arrangement of parts, as will be hereinafter fully described, illustrated in the accompanying drawing, and pointed out in claims hereunto 45 appended.

In the accompanying drawing:—

Figure 1 is a side elevation of a vise constructed in accordance with the invention, showing by dotted lines, a plank to which 50 it is fastened, and by full lines, a bearing shim clamped in the vise.

Fig. 2 is a top plan view showing the 55 shim, by dotted lines, in clamped position.

Fig. 3 is a fragmentary front elevation.

Fig. 4 is a fragmentary vertical longitudinal sectional view through the device.

Fig. 5 is a vertical transverse sectional view on the line 5—5 of Fig. 4, looking in the direction of the arrow.

Similar reference characters indicate corresponding parts throughout the several views in the drawing.

Referring to the drawing in detail. A designates generally a clamp, which in this instance is in the form of a substantially U-shaped frame 10, which is provided at one limb terminal with an eye 11, in which is adjustably engaged the threaded shank 12, of a clamping screw, which at its outer end is formed with a knurled knob 13, while 70 at the opposite inner end is the usual clamp head 14. The other limb 15 of the frame 10, is of substantial dovetail shape in cross sections for detachable engagement in a correspondingly shaped counter-seat or groove 75 16, formed in the under side or bottom of the block or body 17, of the bearing shim vise or holder B, hereinafter described.

The block or body 17 of the vise or holder B, has the counter-seat or groove 16, extending medially from the front to the rear end thereof, so that the block or body 17, can be moved off of the limb 15, either forwardly or rearwardly of the clamp A when engaged upon a plank. Thus the block or 80 body 17, of said vise or holder B, can be readily removed from its clamp A and set within a bench vise of any ordinary construction, or can be fitted on its clamp and thereby be held to a plank or other support. 90

The block or body 17 of the vise B is preferably formed with a rounded front end edge 18, flat straight opposite side edges 19, and the flat straight rear end edge 20, as is clearly shown in Fig. 2 of the drawing, and the 95 straight side edges 19, are designed to make easier the clamping of the vise block or body 17, within a bench vise.

The block or body 17 has secured therein adjacent to its rear edge 20, spaced pin-like 100 stationary jaws or grips 21, which may be vertically adjusted and are formed with inwardly beveled front knife edges 22. The jaws or grips are extended above the top face of the block or body 17 105 to position the knife edges 22 the proper distance above the plane of the top edge of said block or body 17, for the engagement of

the jaws with a bearing shim 23, when the latter is positioned upon the block or body 17, as shown in Figs. 2 and 4.

Intermediate of the block or body 17, and 5 extending through the front edge 18, rearwardly, is a substantially key hole shaped guide slot 24, which at its rear end terminates in a circular bore 25, opening through the rear wall 20 of the block or body 17. 10 The slot 24, opens through the top or upper face of the block or body 17, for a distance thereof, and the closed end of said slot is formed with a forward bevel or incline 26, for a purpose presently described.

15 Suitably fitted within the slot 24 is the shank 27 of a movable jaw 28, which is formed with a concave outwardly beveled inner end 29, providing a curved knife edge 30, the jaw 28, being extended upwardly 20 through the slot 24, beyond the top or upper face of the block or body 17, so that its edge 30 will engage the bearing shim 23 in coöperation with the jaws 21, to clamp the shim upon the top or upper surface of 25 said block or body 17, to securely hold the same in the position shown by dotted lines in Fig. 2 of the drawing. When the shim 23, is clamped by the jaws, it can be readily filed to the desired thinness to fit in bearings.

30 The shank 27 of the movable jaw 28 is formed with a reduced threaded stem 31, which extends through the bore 25, opening through the rear wall 20, of the block or body 17, and has engaged thereon an external knurled elongated nut 32, which works against the block or body 17, and in this manner, the movable jaw 28, is manually adjusted for the clamping or unclamping of 40 a bearing shim in the vise, as is clearly illustrated in Figs. 1, 2 and 4 of the drawing.

One of the salient features of the invention is the disposition of the stationary jaws or grips 21, and the movable jaw 28, relative 45 to each other, that is to say, the stationary jaws or grips 21, are arranged in spaced relation near one edge of the block or body 17, while the movable jaw 28 approaches or recedes at an intermediate point between 50 the stationary jaws or grips 21, and these jaws are formed with knife edges 22 and 30 respectively, to bite the bearing shim when clamped thereby without raising burs, or otherwise displacing the metal at the 55 edges thereof. The beveled wall 26 of the slot 24, and the beveled inner end 29, of the jaw 28, coat to allow said jaws to closely approach the line of the stationary jaws for the clamping of extremely small bearing shims. The adjustment of the jaw 28, relative to the jaw 21, will permit many sizes 60 of bearing shims to be clamped in the vise.

Another important feature of the vise is that the same when mounted upon the clamp 65 A can be fastened to a plank in a work pit

in an automobile repair shop, or said block or body can be detached from the clamp A, so that the vise B, can be fastened, in an ordinary bench clamp for use in clamping bearing shims to be filed in the repair shop proper, as will be clearly apparent.

70 It is to be understood that changes and modifications may be made in the invention, such as come properly within the scope of the appended claims, without departing 75 from the spirit of the invention, or sacrificing any of its advantages.

75 From the foregoing it is thought that the construction and manner of operation of the invention will be clearly understood, 80 and, therefore, a more extended explanation has been omitted.

80 What is claimed is:

1. In a device of the character described, a substantially U-shaped clamp having a 85 straight limb and means on the clamp for engaging a bench or other support, a block having a groove in its under side to slidably receive the limb and thereby made detachable therefrom, jaws mounted in said block above the groove, said jaws being housed within the block but having their engaging faces exposed at the upper face of the block, which face is flat to support the work, the under side of the block coöperating with the engaging means on the clamp to hold the vise in place, and said block when detached from the clamp being capable of insertion in a vise to be held thereby.

90 2. In a device of the character described, 100 a clamp having a straight limb dovetailed in cross-section, and means on the clamp for engaging a bench or other support, a block having a dovetailed groove in its underside to slidably receive said limb, the 105 block being thereby made detachable therefrom, said block having opposite flat sides, jaws housed in said block above the groove and having their engaging faces exposed at the upper face of the block, which face is 110 flat to support the work, the limb being fitted within the groove, said block when detached from the clamp being capable of insertion in an ordinary vise, the flat sides of the block being engaged by the vise.

115 3. In a device of the character described, a block having a flat upper face, a shank housed within the block and slidably movable and having a jaw integral therewith and extending above the upper face of the 120 block, stationary jaws provided on the upper face of the block, on opposite sides of the plane of movement of the first-mentioned jaw, and means for actuating the shank with its movable jaw, said stationary and 125 movable jaws being disposed to engage a shim at spaced points, the flat upper face of the block constituting a support for the shim when engaged by said jaws.

130 4. In a device of the character described,

- a block having a flat upper face and a slot opening through one end and the top thereof, a non-rotatable shank slidable in the slot, a movable jaw formed on the shank 5 and extending above the upper face of the block, a pair of stationary jaws on opposite sides of the slot and at one end of the block to coöperate with the movable jaw thereby providing a three-point engagement with the
- 10 article being held, a threaded stem projecting from the shank through the rear end of the block, and a hand-operated nut adjustably engaged on the stem and working against the block for actuating the movable jaw.
- 15 5. In a device of the character described, a block having a flat upper face and a slot opening through one end and the top thereof, a non-rotatable shank slidable in the slot, a movable jaw formed on the shank and extending above the upper face of the block, a pair of stationary jaws on opposite sides of the slot at one end of the block to coöperate with the movable jaw providing a three-point engagement with the article being held, and means for operating the movable jaw, said jaw being exposed on the upper face of the block and having knife edges formed on their engaging faces.
- 20 6. A vise comprising a block having a flat upper face, a slot extending partly through the block from one end and opening out at said upper face, a movable jaw adapted to and working in the slot and extending through and above the upper face of the block, a stationary jaw protruding upwardly from the upper face of the block, and means by which the movable jaw may be moved toward the stationary jaw, said means being located at one end of the block.
- 25 7. A vise comprising a block, a movable jaw slidable in the block, a stationary two-piece jaw fitted into and detachable from the block, said jaws projecting above the upper face of the block and constituting three dogs by which the work may be held, said upper face of the block being plane to receive the work and brace the same when clamped by the jaws, and means for actuating the movable jaw.
- 30 8. A vise for bearing shims comprising a block having a flat upper face, a holding means housed within the block and extend-
- 35 ing a short distance above the upper face of the same, and means for actuating the holding means to clamp the edges of a shim, the upper face of the block constituting a support for a shim when so clamped.
- 40 9. A vise comprising a block, jaws movable relative to each other in said block, means adapted to move said jaws, the block having a grooved under face, an upper plane face coöoperating with said jaws to hold the work flat thereon, vertical side faces opposite each other providing surfaces for a vise 45 to grip, a curved face joining the side faces providing a surface for a hand to grip, and a fourth side face at right angles to the first-mentioned side faces.
- 45 10. A vise comprising a block, a keyhole-shaped slot extending longitudinally through the greater part of the length of the block, a two-piece stationary jaw fixed to the block and projecting above the same so that one part is on either side of said slot, said jaw 50 being located between the end of the slot and the end of the block, and a jaw slidably movable in the slot and also projecting above the upper face of the block.
- 55 11. A vise comprising a block, a keyhole-shaped slot extending through the block for the greater part of its length, a round slot connecting with the keyhole-shaped slot and forming a continuation of the round part of the same, the two slots together extending through the block from end to end, a stationary jaw fixed to the block, and a jaw slidably movable in the keyhole-shaped slot.
- 60 12. A vise comprising a block, a keyhole-shaped slot extending through the block for the greater part of its length, said slot being open from the upper face of the block, a jaw movable in the keyhole-shaped slot, a stationary jaw provided on the upper face 65 of the block, said movable jaw having an inclined face and the block having a similar inclined face coöoperating therewith, and means for moving the movable jaw.
- 65 In testimony that I claim the foregoing 70 as my own, I have hereto affixed my signature in the presence of two witnesses.
- 75 ANDREW B. LOCKHART.
- Witnesses:
- FRED G. WALTER,
FRANK MACARTNEY.
